UNITED STATES PATENT OFFICE.

LEWIS T. RHOADES, OF MONT CLARE, PENNSYLVANIA, ASSIGNOR TO NEW YORK COIL COMPANY, OF NEW YORK, N. Y.

AUXILIARY AIR-INLET DEVICE FOR INTERNAL-COMBUSTION ENGINES.

1,092,395.

Specification of Letters Patent.

Patented Apr. 7, 1914.

Application filed October 7, 1913. Serial No. 793,799.

To all whom it may concern:

Be it known that I, LEWIS T. RHOADES, a citizen of the United States, residing at Mont Clare, in the county of Montgomery and State of Pennsylvania, have invented certain new and useful Improvements in Auxiliary Air-Inlet Devices for Internal-Combustion Engines, of which the following is a specification.

My invention relates to improvements in auxiliary air-inlet devices for internal combustion engines, an object of the invention being to admit air into the intake of the engine between the carbureter and the cylinders in such proportions as to give increased power and speed without increasing fuel consumption.

A further object is to increase the volume of air drawn into the cylinder in order that the compression within the cylinders will be higher than would be the case if my device were not employed especially when the throttle supplying gas to the engine is only partly opened.

A further object is to provide a device of the above nature which may be installed without boring or defacing the inlet pipe or manifold of the engine to which it is attached and of such simple construction that the most unskilled operator may readily apply the device without resorting to boring or machine work, of any nature.

A further object of the invention is to supply a device of the character described, which can be very cheaply manufactured, namely, punched out by means of the conventional punch press from sheet material without resorting to castings or other expensive operations.

A further object of the invention is my novel valve arrangement, which can be operated not only to increase the efficiency of the engine, but by a second movement may be caused to give a very large opening to the outer air and thus cause the cylinders to cease firing entirely, as this extremely large opening will allow pure air to enter the cylinders instead of gas, not only cooling the cylinders, but also acting as an efficient brake to hold the car in check when descending grades.

A further object of the invention is improved means whereby one valve serves the double purpose of admitting a fixed quantity of air in small proportions and a second

movement admits a very large volume of air with means that will enable the operator to use either the small quantity or the large quantity at will, and at the same time prevent the improper operation of said valve.

With these and other objects in view, the invention consists in certain novel features of construction and combinations and arrangements of parts as will be more fully hereinafter described and pointed out in the claims.

In the accompanying drawings: Figure 1 is a view in elevation illustrating my improvements. Fig. 2 is a view in longitudinal section on the line 2—2 of Fig. 1 showing in full lines the valve in closed position, and in dotted lines in open position, and Fig. 3 is a view in elevation showing one of the plates forming the air chamber removed to illustrate parts within the air chamber.

1 represents a carbureter of any ordinary construction, and 2 an intake pipe adapted to be connected to the cylinders of the engine (not shown). Between the carbureter 1 and the intake pipe 2, my improved device is located, and takes the place of the ordinary gasket or washer used at this point. The bolts 3 and nuts 4 used as clamping means between the carbureter and the intake are utilized to clamp my improved device in position, and hence I can install my device without altering the construction of the engine in the slightest, except to remove the ordinary washer and replace it with my improvements.

My improved device comprises a plurality of metal sheets which are stamped forming three blanks or plates 5, 6, and 7. All of these plates are of the same external shape and are secured together by rivets 8. The intermediate plate or blank 6 is formed with a relatively large opening 9 which when the plates are secured together, forms an elongated air chamber 10. All of the plates have openings 11 in one end for the reception of one of the bolts 3, and a perforated spacing block 12 is secured to the outside plates 5 and bridges the air chamber. This block 12 has its opening 13 registering with openings in the plates 5 and 7 to receive the other of said bolts 3 and allow the device to be clamped firmly in place without contracting the air chamber.

The device projects at one end to one side of the carbureter, and is provided on plate 110

5 with a guide sleeve 14 in which a valve stem 15 slides. The stem 15 is provided with a transverse pin 16 to move in slots 17 in the sleeve 14 and prevent rotary movement of the valve stem. The plate 7 is provided with an opening 18 in which a valve 19 snugly fits. This valve 19 is in the form of a disk having a central sleeve 20 fixed to the stem 15 by means of a transverse pin 21. Valve 19 is provided with a plurality of openings 22, four being illustrated, but I am of course, not limited to any particular number of these openings.

A relatively small coiled spring 23 is located around the stem 15, and bears at one end against the sleeve 14, and at its other end against a washer 24 held on the stem by means of a transverse pin 25. Around the outside of the relatively coiled spring 23, a relatively large coiled spring 26 is located, and this spring 26 bears at one end against the end of sleeve 14, but at its other end terminates short of the washer 24. In other words, when the valve 19 is in closed position against plate 5, the end of spring 26 will be spaced from the washer 24 a distance substantially equal to the thickness of the intermediate plate 6, so that the valve is free to move in a direction to open a portion of its movement without bringing into operation the spring 26 as will be more fully hereinafter explained.

While my invention is not limited to any particular means for operating the valve, I have illustrated an ordinary foot treadle 27 connected by a flexible device 28 with the bent end 29 of stem 15 by means of a screw 30, so that when the pedal is operated, the stem will be moved in one direction against the action of the springs.

It will be noted that when the valve 19 is moved away from plate 5, that air can enter through the openings 22 into the air chamber 10, and flow through this air chamber into the air intake pipe, commingling with the gas in its passage to the cylinders. The openings are so proportioned that when the valve is moved to open position, just the proper quantity of air will be admitted to bring about the best results. This movement of the valve for ordinary admission of air is resisted solely by the relatively small spring 23. If it is desired to admit a large quantity of air, as for example, when coasting or at any other time, to cause the cylinders to cease firing, an excessive pull on the stem 15 against the action of the relatively large spring 26, will move the valve 19 entirely out of the opening 18 in plate 7, so that an inlet, the full capacity of the opening 18, is provided through which the air may be drawn into the cylinders, cooling the cylinders and also acting as a sufficient brake to hold the car in check when descending grades. The two springs 23

and 26 therefore have different functions. The first-named is to resist the normal opening movement of the valve and to return the valve to closed position, while the larger spring 26 only comes into operation when the valve is drawn outwardly beyond normal, assuming normal to be the ordinary inlet of air for the ordinary running of the engine. The spring 26 will be of sufficient strength to require a considerable pressure to move the valve to its extreme open position, so that the operator cannot accidentally admit too much air, yet can designedly do so whenever desired.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. Means for admitting air to internal combustion engines, comprising an air chamber having an opening in its wall, a valve movable in said opening and seated against the inner wall of the chamber at the opposite side of the chamber, said valve having perforations therein through which air is admitted to the chamber when the valve is drawn away from the inner wall thereof, and means permitting the valve to be drawn entirely out of the first-mentioned opening to admit an abnormal quantity of air, substantially as described.

2. Means for admitting air to internal combustion engines, comprising an air chamber having an opening in its wall, a valve movable in said opening and seated against the inner wall of the chamber at the opposite side of the chamber, said valve having perforations therein through which air is admitted to the chamber when the valve is drawn away from the inner wall thereof, a stem on said valve, two coiled springs on the stem, one longer than the other, and a shoulder on the stem against which the longer spring bears and against which the larger spring is brought into contact when the valve is moved to a position to be drawn out of the said opening, substantially as described.

3. Means for admitting air to internal combustion engines, comprising an air chamber having an opening in its wall, a valve movable in said opening and seated against the inner wall of the chamber at the opposite side of the chamber, said valve having perforations therein through which air is admitted to the chamber when the valve is drawn away from the inner wall thereof, a stem on said valve, two coiled springs on the

stem, one longer than the other, a shoulder on the stem against which the longer spring bears and against which the larger spring is brought into contact when the valve is moved to a position to be drawn out of the said opening, and means preventing rotary movement of the stem, substantially as described.

4. A device of the character described, comprising an air inlet chamber adapted to be positioned between a carbureter and an intake pipe, and having openings in its opposite walls registering with both said carbureter and said intake pipe, said chamber having an air inlet opening in its wall, and a spring held perforated disk controlling the passage of air through said inlet, and said disk adapted to be drawn entirely out of the opening in the wall, substantially as described.

5. A device of the character described, comprising three plates riveted together and of uniform external contour, said intermediate plate having a relatively large opening forming an elongated air chamber, said outside plates having registering openings adapted to register with the outlet of a carbureter and the end of an intake pipe respectively when said device is clamped between the carbureter and the intake pipe, and means controlling the inlet of air to said chamber, substantially as described.

6. A device of the character described, comprising three plates riveted together and of uniform external contour, said intermediate plate having a relatively large opening forming an elongated air chamber, said outside plates having registering openings adapted to register with the outlet of a carbureter and the end of an intake pipe respectively when said device is clamped between the carbureter and the intake pipe, one of said outside plates having an opening therein, and a perforated spring held valve positioned in said opening, substantially as described.

7. A device of the character described, comprising three plates riveted together and of uniform external contour, said intermediate plate having a relatively large opening forming an elongated air chamber, said outside plates having registering openings adapted to register with the outlet of a carbureter and the end of an intake pipe respectively when said device is clamped between the carbureter and the intake pipe, one of said outside plates having an air inlet opening therein, a perforated disk valve in said opening, a stem secured to the valve and projecting through the other of said outside plates, and a spring on said stem normally holding the disk valve against the last-mentioned plate, substantially as described.

8. A device of the character described, comprising three plates riveted together and of uniform external contour, said intermediate

plate having a relatively large opening forming an elongated air chamber, said outside plates having registering openings adapted to register with the outlet of a carbureter and the end of an intake pipe respectively when said device is clamped between the carbureter and the intake pipe, one of said outside plates having an air inlet opening therein, a perforated disk valve in said opening, a stem secured to the valve and projecting through the other of said outside plates, two coiled springs on said stem, a shoulder on the stem against which one of said coiled springs normally bears and against which the other of said coil springs bears when further movement in the same direction is imparted to the stem, substantially as described.

9. A device of the character described comprising an air chamber having an opening at one end to communicate with the intake pipe of an internal combustion engine, said air chamber having a valve receiving opening, a valve fitting said opening, and having openings therein, and means for moving the valve through the opening and entirely out of the opening, substantially as described.

10. A device of the character described, comprising an air inlet chamber adapted to communicate with the intake of an engine, said chamber having an opening in one wall, a valve fitting said opening, a spring adapted to press said valve against the opposite wall of the chamber, and said valve having air inlet openings therein through which air will enter the chamber when the valve is drawn away from the last-mentioned wall, and said valve adapted to be drawn entirely out of the opening in the wall, substantially as described.

11. A device of the character described, comprising an air inlet chamber adapted to communicate with the intake of an engine, said chamber having an opening in one wall, a valve fitting said opening, a spring adapted to press said valve against the opposite wall of the chamber, said valve having air inlet openings therein through which air will enter the chamber when the valve is drawn away from the last-mentioned wall, and a second spring resisting the opening action of the valve to draw the same entirely out of the opening in the wall, substantially as described.

12. A device of the character described, comprising an air inlet chamber adapted to communicate with the intake of an engine, said chamber having an opening in one wall, a valve fitting said opening, a spring adapted to press said valve against the opposite wall of the chamber, said valve having air inlet openings therein through which air will enter the chamber when the valve is drawn away from the last-mentioned wall, a

second spring resisting the opening action of the valve to draw the same entirely out of the opening in the wall, said springs both positioned around a stem secured to the 5 valve, and the last-mentioned spring shorter than the first-mentioned spring, substantially as described.

In testimony whereof I have signed my name to this specification in the presence of two subscribing witnesses.

LEWIS T. RHOADES.
